UNITED STATES PATENT OFFICE.

JOHANN G. PETERSON AND OTTO H. HUEBEL, OF JERSEY CITY, NEW JERSEY, ASSIGNEES TO MANHATTAN ELECTRICAL SUPPLY COMPANY, INC., OF JERSEY CITY, NEW JERSEY, A CORPORATION OF NEW JERSEY.

TELEGRAPH-KEY.

1,242,470.

Specification of Letters Patent.

Patented Oct. 9, 1917.

Application filed March 17, 1917. Serial No. 155,446.

To all whom it may concern:

Be it known that we, JOHANN G. PETERSON and OTTO H. HUEBEL, citizens of the United States, residing at Jersey City, in the county of Hudson and State of New Jersey, have invented certain new and useful Improvements in Telegraph-Keys, of which the following is a specification.

This invention relates to telegraph-keys. 10 From time immemorial so far as we are aware, a telegraph key comprises a lever provided with a contact or "point," as it is sometimes known. This contact or point is coöperative with a fixed contact point carried by the base of the key lever. These old contacts or points are permanently connected with the lever and base respectively, so that as a consequence it is an exceedingly difficult and sometimes practically-impossible matter to replace them. We eliminate this defect in an eminently satisfactory manner, providing an organization wherein either or both contacts can be readily and instantly removed.

25 In the drawings accompanying and forming part of the present specification we have shown in detail one convenient form of embodiment of the invention which will be set forth fully in the following description, so that those skilled in the art can practise the invention. We do not restrict ourselves to this particular disclosure, however, as we may depart therefrom in several ways within the scope of the invention defined by the 35 claims following said description.

Referring to said drawings:

Figure 1 is a top plan view, and

Fig. 2 is a side elevation of a telegraph-key involving the invention.

40 Fig. 3 is a transverse section on the line 3—3 of Fig. 2, looking in the direction of the arrow and on a larger scale.

Fig. 4 is a detail view in perspective about on the scale of Fig. 3 of the two contacts 45 and the carrier for the key-contact.

Like characters refer to like parts throughout the several figures of the drawings.

In Figs. 1 and 2 the numeral 2 denotes 50 the base and 3 the lever of a Morse key, the base being provided with the usual adjuncts and means to attach it to a suitable support. On the upper side of the base are the lugs 4 through which are threaded screws 5,

having pointed sockets at their inner ends 55 to receive the pivot 6 of the key-lever 3. Said key-lever is provided at its front end with the customary button 7 and at its rear end is furnished with the screw 8 by which the degree of movement of the key lever 3 60 can be regulated as well understood. Through the lever 3 between its fulcrum or center of motion and the button is threaded a screw 9 acted upon by the spring 10 which retracts the lever, the advance of said 65 lever being accomplished manually as is known. The foregoing is a concise description of a familiar form of key in which our improvement can be advantageously incorporated, although obviously we are not restricted in this particular. The present type of key as is understood has a contact or point coöperative with a similar part on the base, and we provide a construction wherein either or both of these contacts or 70 points or as they are sometimes known "contact points" can be removed without disassembling the key, which is a feature of importance.

A contact or point which can be advantageously carried by the key may vary, although that denoted in a general way by 11 answers our requirements in a satisfactory manner. The contact or point carried by the base in like fashion may vary within 80 limits, although that denoted by 12 has met our conditions. The contact 11 is as illustrated removably connected in some convenient manner with a carrier as 13 which in turn is preferably removably connected with 85 the lever 3. As shown the carrier 13 comprises the base 14, the upright portion 15 and the overhanging part 16, the base 14 having a threaded opening to receive the threaded shank 17 of the removable contact or point 90 11. This base 14 as shown fits against the under side of the key lever 3, the upstanding portion 15 being contiguous to one side of the key lever and the projection 16 overhanging said lever as shown best in Fig. 3. To hold 95 the carrier 13 in place any convenient means may be provided, the screw 18 being shown for this purpose. Said screw is tapped through the arm 16 and its pointed lower end is adapted to fit an opening as 19 in the upper side of the key lever to thus aid in holding the carrier 13 in assembled relation with the key lever. This positioning of the car-

rier is further aided by the fact that the base 14 has lugs as 20 which overlie the side of the lever opposite the upstanding portion 15, all as shown fully in Fig. 3. When, 5 therefore, the holding screw 18 is set, the contact or point 11 provided it be in assembled relation with the carrier 13, is properly held in operative condition with the base or coöperating contact or point 12 in as secure 10 a manner in fact as in the old and common structure. Should it be necessary to remove the point 11 for repairs or substitution, this can readily be accomplished without taking the carrier 13 from the lever 3, by simply 15 elevating the forward branch of the lever 3 sufficiently to unscrew the shank 17 from the base 14. Or in lieu of this, and when occasion requires, the carrier 13 as a unit with its contact can be removed by simply back- 20 ing out the screw 18 enough to take its pointed end from the socket 19 when the carrier can be moved sidewise from the key lever. In both these cases either removal can be effected easily and quickly without 25 disassembling any of the keys. The same function, as will be hereinafter apparent can be accomplished with the normal fixed contact or point 12.

The base 2 has a perforation to receive 30 the bushing 21, the head 22 of the bushing overlying the base, and the washer 23 of suitable insulating material being interposed between said head and the base. Through 35 this bushing is extended the screw 24, which receives at its lower end the nut 25 set in the counterbore 26 in the under side of the base, the insulating washer 27 being interposed between the nut and the bushing 21. The screw 24 has a head 28 which overlies 40 the head 22, the conducting bridge 29 being interposed between the two heads and extending to the post 30 as common. To the post 30 is connected one of the leads. The

screw 24 presents a suitable carrier for the contact 12, which is, of course, virtually co- 45 axial with the contact 11. This contact 12 has the threaded shank 31 entering a correspondingly threaded opening in the center of the screw 24. Said contact further has a shouldered portion 32 rigid and usually integral therewith and which may as shown 50 be of hexagonal or other suitable polygonal shape and which when the contact 12 is positioned bears against the head 28. By elevating the key lever 3 sufficiently the contact 55 24 can be easily unscrewed from its carrier 24.

What we claim is:

1. A telegraphic key comprising a lever, a carrier having a base furnished with an upstanding portion provided with an arm which overhangs the lever, the base being fitted against the lower side of the lever, a screw threaded through the arm and pointed at its lower end, the lever having an opening 60 to receive the pointed end of the screw, and a contact removably carried by the base.

2. A telegraphic key comprising a lever, a carrier having a base furnished with an upstanding portion provided with an arm 70 which overhangs the lever, the base being fitted against the lower side of the lever, a screw threaded through the arm and pointed at its lower end, the lever having an opening 75 to receive the pointed end of the screw, and a contact threaded into the base, the base having projecting means which overlie the lever opposite said upstanding portion.

In testimony whereof we affix our signatures in the presence of two witnesses.

JOHANN G. PETERSON.
OTTO H. HUEBEL.
